[57] CLAIM

The ornamental design for vertically adjustable ball cock, as shown and described.

DESCRIPTION

FIG. 1 is a front elevational view of a vertically adjustable ball cock showing my new design;

FIG. 2 is a top plan view thereof;

FIG. 3 is a bottom plan view thereof;

FIG. 4 is a left side elevational view thereof;

FIG. 5 is a rear elevational view thereof; and

FIG. 6 is a right side elevational view thereof.

The broken line representation of a float and its connecting rod in FIG. 1 is for purposes of illustration only.

*Fig. 1**Fig. 4.**Fig. 2.**Fig. 3.**Fig. 5.*

Fig. 6.
